TRACK CLEANING CAR

Kenneth Van Dyck, Westport, Conn., assignor to The Lionel Corporation, New York, N.Y., a corporation of New York

Application November 5, 1957, Serial No. 48,350

Term of patent 14 years

(Cl. D34—15)

Fig. 1 is a perspective view of a track cleaning car, showing my new design;

Fig. 2 is a side elevational view, the opposite side being substantially a mirror image thereof;

Fig. 3 is a top plan view; and

Fig. 4 is a left end elevational view thereof.

I claim:

The ornamental design for a track cleaning car, as shown and described.
